Primary Examiner — Sheryl Lane*Assistant Examiner* — Emily A Caven(74) *Attorney, Agent, or Firm* — Daniel M. Cohn; Howard M. Cohn(57) **CLAIM**

The ornamental design for a cat scratching post, as shown and described.

DESCRIPTION

FIG. 1 is a perspective view of a cat scratching post showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of a portion of the post surface shown in FIG. 4;

FIG. 10 is an enlarged view of a portion of the surface of the ball as shown in FIG. 4; and,

FIG. 11 is an enlarged view of a portion of the surface of the article's base shown in FIG. 4.

The broken lines define the bounds of the claimed design and form no part thereof.

1 Claim, 11 Drawing Sheets(56)
